Specification of Letters Patent. Patented Mar. 12, 1918.

Application filed November 4, 1915. Serial No. 59,507.

To all whom it may concern:

Be it known that we, MALCOLM F. EWEN and ARTHUR L. S. McCURDY, the former a citizen of the United States and the latter 5 a subject of Great Britain, and residents of Chicago, in the county of Cook and State of Illinois, have invented certain new and useful Improvements in Refrigerating Apparatus; and we do hereby declare that the following is a full, clear, and exact description thereof, reference being had to the accompanying drawings, and to the letters of reference marked thereon, which form a part of this specification.

15 This invention relates to improvements in refrigerating apparatus and consists of the matters hereinafter described and more particularly pointed out in the appended claims.

The invention relates to a refrigerating apparatus of the absorption type which includes in general a generator or still, an absorber, a combined condenser and liquid receiver and an expansion chamber or coil, and in addition, includes a valve interposed 25 between the liquid receiver and the expansion chamber or coil for controlling the admission of liquid refrigerant thereto.

The improved apparatus is of the kind known as a continuously operating apparatus in which the generator or still and the absorber are always used respectively as a still and as an absorber and are continuously subjected, in the normal operation of the apparatus, the one to heat and the other 35 to the action of a cooling agent. Means are provided for withdrawing the liquid saturated with the refrigerant from the absorber and for delivering it into the still, and the pressure generated by the still is 40 made use of to force the desaturated weak liquor from the still to the absorber.

The apparatus herein disclosed is of the same general type as that described in an application heretofore filed by Malcolm F. 45 Ewen, on the 4th day of January, 1915, Serial Number 393, and the specific embodiment of the invention shown herein is a species of the genus to which the apparatus of the above named application belongs.

50 The essential idea of the apparatus claimed in this case, as well as of that in the application referred to, is to so correlate the generating part of the apparatus on the one hand and the refrigerating part of the 55 apparatus on the other hand that the charge

in the liquid receiver, the one part of the apparatus which is common to both sides, will be renewed from the generator in proportion as it is exhausted to the expansion chamber so that the part of the charge taken 60 from the liquid receiver is substantially replaced by an equal or proportional amount put back into the receiver.

In the apparatus described in the application referred to, a water motor driven 65 pump was shown which constituted both a measuring device and the means for transferring the absorbent from the absorber to the still in certain timed relation with the operation of the valve connecting the still 70 with the expansion chamber, thereby bringing about the correlation between the two sides of the apparatus above referred to. There are several objections to the use of a pump for this purpose. First, in an apparatus of the kind, it does not constitute 75 as efficient a measuring device as it might be. In the second place, a water-motor-driven pump of the kind described, depending upon the water pressure for the operation of the motor, is not capable of use under all circumstances, as the pressure provided in ordinary municipal systems is not always sufficient to bring about the required operation. In addition, the water motor is 80 not economical, as it requires more water for its operation than is necessary for the supply of cooling water in the operation of the apparatus, so that the excess water is 85 wasted so far as its use as a cooling agent 90 is concerned.

In the present invention, there is provided a receptacle for measuring the quantity of absorbent to be transferred from the absorber to the still in the desired timed relation with the operation of the valve connecting the receiver with the expansion chamber, said receptacle having inlet and outlet valves that require very little power for their operation. The receptacle is connected directly to the still, which is arranged at a lower level, so that gravity may be used as the force for transferring the predetermined measured amount of absorbent to the still when the outlet valve of the receptacle is opened to connect said receptacle and still.

Thus any motor device required for the operation of the valves of the receptacle may be slow acting and of little power so 110

that where a water motor is used for the operation of the valves, a very small amount of water at low pressure is required, making it possible to use a small by-pass from the supply pipe that supplies the required amount of cooling water for cooling the absorber.

The advantages of our invention will appear more clearly as we proceed with our specification.

In the drawings:

Figure 1 is a view representing our improved refrigerating apparatus in front elevation.

Fig. 2 is a view representing a transverse plan section through Fig. 1 in a plane indicated by the line 2-2 of Fig. 1.

Fig. 3 is a detail sectional view on an enlarged scale showing the device by means of which the strong liquor is conducted from the absorber to the still in predetermined measured amounts at predetermined intervals.

Fig. 4 is a view representing a transverse section through one of the valve plugs of the device shown in Fig. 3, in a plane indicated by the line 4-4 of Fig. 3.

Fig. 5 is a view representing a vertical central section through the cooling tank and the absorber and combined condenser and liquid receiver contained therein.

Fig. 6 is an enlarged detail sectional view of the head of the absorber and of the valve means that controls the flow of weak liquor thereto.

Fig. 7 is a sectional view of a valve that controls the flow of combined condenser and liquid refrigerant from the liquid receiver to the expansion coil.

Fig. 8 is a detail, perspective view illustrating a part of a valve stem and its associated actuating cam, embodied in our invention.

The apparatus illustrated herein as an embodiment of our invention is designed more particularly for the use of ammonia as the refrigerant and of water as the absorbent, and hereinafter, without further explanation, we shall so describe it, but it will be understood that the improved apparatus is not necessarily limited to the use of such refrigerant and of such absorbent.

Referring now to the apparatus illustrated in the drawings:—10 indicates the generator or still, 11 indicates the absorber, 12 indicates the combined condenser and liquid refrigerant receiver, 13 indicates the pipe leading from the combined condenser and liquid receiver to the expansion chamber or coil 14, and 14* indicates the return pipe leading from the said expansion chamber or coil back to the absorber and adapted for returning the vaporized, expanded refrigerant, ammonia gas, to the absorber 11, wherein it is taken up and absorbed by the

liquid absorbent, water, contained therein. The admission of the liquid refrigerant to the expansion coil or chamber is controlled by a valve mechanism 15 interposed in the pipe 13, which valve mechanism is operated 70 to positively open the valve automatically and periodically in a manner presently to be described.

Any convenient means may be used for heating the still or generator 10 and we 75 have illustrated herein to that end the familiar gas burner. 16 indicates such a burner, the same consisting of a large pipe extending longitudinally below the still 10 in a position to heat it and being provided 80 with suitable orifices for the escape of the fuel gas supplied to it from any suitable source. The still 10 is in the form of an elongated drum and is preferably surrounded at the top, sides and ends by means of 85 a heat insulating jacket 17 of any suitable or desirable construction. A stack 18 fixed near one end to the top of the jacket is provided for the escape of the products of combustion. The burner is intended to burn 90 all the time that the apparatus is in operation and may be controlled by any suitable hand valve.

The absorber 11 and the combined condenser and liquid receiver 12 are preferably 95 made as illustrated, in the form of upright, elongated, cylindric shells closed at top and bottom. Said shells are supported in any convenient way in an upright tank 21 which is constructed to contain cooling water. 100 Said tank is supported by upright metal angle bars 22 secured to its upright corners and also providing a support for the still 10 and for its jacket 17. The uprights 105 themselves are supported on skids 22* which raise them above the floor 22* upon which the apparatus rests.

The still 10 is connected to the combined condenser and liquid receiver 12 by means of pipes 24, 24, rising from the top of the 110 still. Said pipes rise a short distance vertically above the still and are then carried back of the rear wall of the tank 21 and then vertically upward to a point above the tank where they are joined together and to 115 a common discharge pipe 25 which enters the combined condenser and liquid receiver 12 at the top. The pipes 24, 24, constitute a rectifier in which the water vapor carried from the still with the ammonia gas is condensed and returned to the still. 120

The absorber 11 is connected with the still by means of a pipe 26. The said pipe is disposed vertically and its upper end is connected to the bottom of the absorber 125 while its bottom end is connected to the top of the still. In this pipe is interposed an automatic measuring and transferring device which acts periodically to draw off from the absorber a predetermined amount 130

of the strong liquor and to direct said amount into the still. This device thus accurately measures the amount of strong liquor conducted at each of its operations 5 from the absorber to the still and as will later appear, the means which actuates this measuring device also actuates the valve that conducts the liquid ammonia from the combined condenser and liquid receiver to 10 the expansion chamber or coil, thus maintaining the correlation hereinbefore referred to.

27 indicates as a whole the measuring device referred to. The same consists as shown 15 herein of a receptacle adapted to contain a certain predetermined amount of liquor and of inlet and outlet valves adapted to control the flow of liquor first from the absorber to fill said receptacle and next from said receptacle into the still. 28 indicates the receptacle, which in this case, consists of two casings 28^a, 28^b, connected by means of a pipe 28^c. In one casing, namely, the casing 28^a, is located the inlet valve 29 and in the 25 other casing is located the outlet valve 30. The receptacle is thus preferably made in this way in order to simplify the valve constructions. The casing 28^a consists of a sleeve 31, having an integral closed end 32 and closed at its other end by means of a threaded plug 33. The inner bore or the sleeve is reduced near one end to provide a valve seat 34, against which is adapted to close a valve plug 35, the reduced end 36 of 30 which has bearing in the smaller part of the sleeve. A spring 37 is interposed between the valve and the threaded closing plug 33 of the sleeve in such manner as to normally hold said valve closed on its seat. Preferably the valve plug has an annular gasket 35^a to make a tight joint against the seat. A valve stem 38 is fixed to the valve plug 35 and has bearing in a passageway bored through the integral end 32 of the valve 35 casing. A stuffing box 39 is provided to prevent leakage. One part of the pipe 26, namely, the part 26^a, is secured in a threaded nipple that gives access to the casing 35 on the inlet side of the valve seat.

50 The casing 28^b is of the same construction and like parts are lettered with the same numerals with the superscript ". The space between the integral head of the casing 32^b and the valve seat 34^b in this case is made longer than in the case of the head and valve seat of the casing 28^a. The casing 28^b at a point on the outlet side of the valve seat 34 is connected by the pipe 28^c with the part of the casing 28^b on the inlet side of its 55 valve seat 34^b. The outlet end of the casing 28^b is connected by a pipe of comparatively large diameter, 26^b, directly with the still 10. In this pipe is preferably interposed a hand valve 26^d. Each of said casings 28^a, 28^b, are mounted in a small auxiliary cooling

tank 40, the reduced ends of said casings being as shown, secured in one upright wall of said tank.

The valve stems 38, 38^b, are provided with trip ends 41, 41^b, which are rigid 70 against a blow given in one direction, but will flex if struck in the opposite direction. The trip end 41 is arranged so that it will flex in the direction in which the end 41^b is rigid and vice versa.

75 The valve stems 38, 38^b, are actuated by means of a water motor 42, (see Figs. 1 and 2), arranged horizontally above and somewhat in front of the still 10 and suitably supported on the upright angle bars 22. 80 This water motor is, as shown, of piston-cylinder construction and is supplied with a small amount of water in such manner as to impart a slow reciprocating movement to its piston rod.

85 43 indicates the piston rod of said water motor. It is extended over into the neighborhood of the valve 15 that controls the flow of refrigerant into the expansion coil. Said piston rod carries a frame 44 upon 90 which is fixed two cam bars, namely, a cam bar 45 and a cam bar 45^b. These bars are arranged to engage the trip ends 41, 41^b, of the valve stems 38, 38^b. Said bars have inclined ends 46, 46^b, at both ends 95 and are adapted, when they strike the trip ends of their respective valve stems, to move said valve stems to open the respective valve and to hold said valves in open position during a predetermined time interval—that is to say, the time that it takes the piston rod 43 to carry the length of the cam bar beyond the valve stem. It will be manifest that when the piston rod 43 is moved in one direction the valve 35 105 will be lifted from its seat and held in that position for a predetermined length of time, whereupon it will be closed, the other valve 35^b being closed on its seat during this time; that when said piston rod moves in 110 the return direction, the valve 35^b will be opened and held open during a predetermined period, the first named valve 35 being closed on its seat during this time.

115 The operation of the measuring-transfer device is as follows:—when the valve 35 is opened, the strong liquor is caused to flow by gravity from the absorber into the casing 28^a, filling the same and (by reason of the connection of said casing with the inlet end 120 of the casing 28^b, through the pipe 28^c) filling the inlet end of the casing 28^b. In other words, when the valve 35 is opened, the measuring receptacle (comprised by the two casings and their connecting pipe from inlet 125 valve seat 34 to the outlet valve seat 34^b) is filled from the absorber. The flow from the receptacle is prevented by the closed valve 35^b. When the cam bar 45 has passed beyond the valve stem 38, the spring 37 will 130

cause the inlet valve 35 to close, thus closing off the measuring receptacle from the absorber.

Upon the return movement of the piston rod 43, the valve 35* is raised from its seat, thus opening communication between the receptacle and the still. As the pipe 26* is of large diameter, the high pressure in the still due to the heat of generation, does not prevent the liquor in the receptacle from flowing into the still. The receptacle is thus drained into the still 10.

While the outlet valve 35* is open, the generated refrigerant in the top of the still, 15 of course, flows into and fills the receptacle and adds its pressure to that of the spring 37 in maintaining the inlet valve 35 closed on its seat. During the return movement of the motor piston rod, the valve 35* is closed 20 on its seat, thus cutting off communication between the receptacle and the still. The refrigerant gas retained in the receptacle is cooled by the cooling water in the auxiliary cooling tank 40 so as to greatly reduce this 25 pressure. In the next forward movement of the piston rod 43, the valve 35 is opened, such small amount of gas as is contained in the receptacle passing through the pipe 26* into the absorber under comparatively low 30 pressure, and being quickly absorbed therein. The liquor then passes from the absorber into the receptacle as before and the action continues.

The weak liquor is discharged in a familiar manner from the still into the absorber under the pressure within the still 35 through a pipe 47, connected to the bottom of the still and opening into the top of the absorber 11. A discharge spray ring located 40 in the top of the absorber is connected with this pipe so that the weak liquor is discharged in the form of rain through the ammonia gas in the top of the absorber, so that it will rapidly and quickly absorb the 45 gas.

In the pipe 47 is preferably interposed a cooling coil 47*, which is located in the cooling tank 21 and in a compartment thereof which is separated from the compartment 50 containing the absorber and the combined condenser and liquid receiver by means of an upright partition wall 48, as in the case of the application hereinbefore referred to. This partition wall prevents 55 the water in the cooling tank, which is subjected to the heat of the coils through which the weak liquor passes, from coming into direct contact with the absorber and the combined condenser and liquid receiver. 60 A valve mechanism 49 controls the flow of the weak liquor to the absorber as in the previously referred to case, the opening and closing movement of said valve being controlled by a float 50.

65 The valve 15 which controls the flow of

liquid refrigerant into the expansion chamber or coil is operated by a lever 51 just as in the case of the apparatus in the prior mentioned application. This lever is weighted in such manner as to normally hold the 70 valve in closed position and is adapted to be raised to open the valve by means of a device 52 fixed on the piston rod 43 of the water motor that actuates the valves in the measuring device. The device 52 is slidably 75 mounted upon the piston rod 43 and is provided with a set screw 52* so that it may be adjusted on the bar to properly correlate with the position of the frame 44 that actuates the valves of the measuring-transfer receptacle. The said device, instead of having one tooth to actuate the lever, is provided with several teeth 52*, which will cause several opening and closing movements of the valve while the piston rod 43 is moving its 85 predetermined length.

The cooling water is supplied to the tank 21 from a pipe 53. A small amount of the water from this pipe is directed through a by-pass 53* into the water motor 42 for 90 driving said motor. The flow of water through this by-pass pipe is controlled by a hand valve 54. The exhaust from the motor is conducted through a pipe 55 which discharges into the tank 40 that contains the 95 measuring device. The overflow from the tank 21 and from the tank 40 is conducted respectively by pipes 56, 57, through a pipe 58, leading to a sewer or other place for disposal of the water.

100 It will be manifest upon consideration of the operation of the apparatus that the measuring device may be used in determining the amount of refrigeration that is to be performed by the apparatus, since, by 105 changing the cubical content of said measuring device or by changing the frequency of its action, the amount of refrigerant delivered to the combined condenser and liquid receiver for use in the expansion chamber may be varied and thus the capacity of a given apparatus be increased or diminished.

110 While in describing our invention, we have referred to certain details of construction and arrangement, it is to be understood that our invention is to be in no way limited thereby except as pointed out in the appended claims.

115 We claim as our invention:

1. In a refrigerating apparatus of the kind described, in combination with a still, an absorber, a combined condenser and liquid receiver, an expansion chamber and conduits connecting the said several parts, a 120 valve interposed between said combined condenser and liquid receiver and said expansion chamber, a measuring device intermediate the absorber and the still for measuring predetermined amounts of saturated ab- 125 130 135 140 145 150 155 160 165 170 175 180

- sorbent to be transferred from the absorber to the still, the still being located below said receptacle, means for operating said valve, and means for transferring by gravity the 5 contents of said measuring device to said still at predetermined intervals in timed relation with the operation of said valve.
2. In a refrigerating apparatus of the kind described, in combination with a still, 10 an absorber, a combined condenser and liquid receiver, an expansion chamber, a valve interposed between said combined condenser and liquid receiver and said expansion chamber, and conduits connecting said 15 several parts, a measuring device interposed between said still and said absorber, said still being located below said measuring device, means for connecting said measuring device in alternation with said absorber and 20 with said still, and means for operating said valve in timed relation with the means which connect said receptacle with said still.
3. In a refrigerating apparatus of the kind described, in combination with a still, 25 an absorber, a combined condenser and liquid receiver, an expansion chamber, a controlled valve between said combined condenser and liquid receiver and said expansion chamber, and conduits connecting said 30 several parts, a measuring receptacle located between said absorber and said still, said still being located below said measuring receptacle, inlet and outlet valves in said receptacle adapted to be operated in alternation, and means for opening the inlet valve 35 of said receptacle and for operating the controlling valve to the expansion chamber in predetermined timed relation.
4. In a refrigerating apparatus of the kind described, in combination with a still, 40 an absorber, a combined condenser and liquid receiver, an expansion chamber, a positively operating valve connecting said combined condenser and liquid receiver and
- said expansion chamber, and conduits connecting said several parts, a measuring receptacle interposed between said absorber and said still, inlet and outlet valves provided in said receptacle, the one connecting it with the absorber and the other connecting it with the still, means for operating said valve to open and close them in alternation, and means for actuating said positively operating valve connected with the expansion chamber in timed relation with the 50 opening of the outlet valve, of said receptacle.
5. In a refrigerating apparatus of the kind described, in combination with a still, 55 an absorber, a combined condenser and liquid receiver, an expansion chamber and conduits connecting said several parts, a measuring device interposed between said still and said absorber adapted to measure predetermined quantities, the said device 60 consisting of a receptacle provided with inlet and outlet valves, said valves being adapted to be operated in alternation, a pipe connecting the inlet side of said receptacle with said absorber, a pipe of comparatively large 65 diameter connecting the outlet side of said receptacle with the still, a positively operating valve interposed between said combined condenser and liquid receiver and said expansion chamber, and means for actuating 70 said inlet and outlet valves of the measuring device in alternation and said positively operating valve in fixed timed relation with said inlet and outlet valves.

In testimony that we claim the foregoing 80 as our invention we affix our signatures in the presence of two witnesses this 18th day of October, A. D. 1915.

MALCOLM F. EWEN.
